CLAIM

The ornamental design for a toddler hooded stroller bag, as shown and described.

DESCRIPTION

FIG. 1 is a front elevational view of the toddler hooded stroller bag showing our novel design in use by a toddler;

FIG. 2 is a rear elevational view thereof;

FIG. 3 is a right side view thereof;

FIG. 4 is a left side view thereof;

FIG. 5 is a top plan view thereof; and,

FIG. 6 is a bottom plan view of the toddler hooded stroller bag of the present invention.

The broken line showing of a partial human face in FIG. 1 is for illustrative only and forms no part of the claimed design. Other broken lines shown on the claimed design represent conventional stitching or surface treatment resembling stitching.
